UNITED STATES PATENT OFFICE.

THOMAS L. TALIAFERRO, OF CHICAGO, ILLINOIS, ASSIGNOR TO PHOENIX HERMETIC COMPANY, OF CHICAGO, ILLINOIS, A CORPORATION OF NEW YORK.

THREADING AND CURLING DEVICE FOR METAL CAPS.

Application filed March 16, 1923. Serial No. 625,634.

To all whom it may concern:

Be it known that I, THOMAS L. TALIAFERRO, a citizen of the United States, residing at Chicago, in the county of Cook, State 5 of Illinois, have invented certain new and useful Improvements in Threading and Curling Devices for Metal Caps, of which the following is a description; reference being had to the accompanying drawing, and 10 to the figures of reference marked thereon.

The invention relates to new and useful improvements in threading and curling devices for metal caps, and more particularly to threading and curling rolls which 15 cooperate to simultaneously thread the flange of a metal cap and curl the lower edge thereof.

An object of the invention is to provide a threading and curling mechanism wherein 20 the curling sections may yield relative to each other independently of the threading sections to accommodate varying thicknesses of metal whereby the edge may be properly curled and threads rolled in the flange of 25 the cap of proper depth.

A further object of the invention is to provide a threading mechanism consisting of inner and outer threading rolls, each of 30 which is provided with a curling section, a threading section and a knurling section, wherein the outer threading roll is so constructed that the curling section can yield to excessive pressure if the thickness in the 35 metal should vary so that threads of uniform depth may be rolled even though the thickness of the metal from which the cap is made should vary.

These and other objects will in part be 40 obvious and will in part be hereinafter more fully disclosed.

In the drawings which show by way of illustration—

Figure 1 is a view showing an inner and outer threading roll embodying my improvements, the outer threading roll being 45 sectioned to show the manner of mounting the curling section, the threading rolls being spaced from each other;

Fig. 2 is a view similar to Fig. 1, but 50 showing only a part of the lower or inner threading roll and the two rolls in engagement with the cap for threading and curling the edge thereof;

Fig. 3 is a section on the line 3—3 of 55 Fig. 1, and

Fig. 4 is a section on the line 4—4 of Fig. 1.

The invention is directed broadly to a threading mechanism for threading and curling the edge of a metal cap. In carrying out the invention, I use two cooperating thread rolls. The cap is first blanked out so as to provide a body portion having a depending flange, the lower edge of which extends outwardly substantially at right 60 angles to the flange. This blank is placed on the inner threading roll, after which the outer threading roll is brought into rolling contact with the inner threading roll, and the threads rolled in the flange at the same 65 time that the edge of the cap is curled. I also prefer to use a knurling section which 70 simultaneously knurls the flange as it is threaded and curled. In devices of this character which have been heretofore used, the curling section and the threading section of each roll are rigidly supported so 75 that they move together, but have no independent movement relative to each other. It will readily be seen that when the edge 80 of the cap is rolled, if the thickness of the metal increases, the roll is going to be slightly increased. This increased thickness of metal will limit the inward movement of the outer curling section. Inasmuch 85 as the threading section has heretofore been made rigid with the curling section, the inward movement of the threading section will also be limited by the thickness of the 90 metal in the curl and this will prevent the rolling of the threads of uniform and proper depth.

The invention is directed particularly to the mounting of the threading and curling sections on the outer roll, so that they may 95 have a yielding movement relative to each other. I prefer to mount the curling section so that normally it is concentric with the center of rotation of the roll, but under excessive pressure, said outer curling section 100 is capable of lateral movement of the roll so as to permit the threading section to move into proper cooperative action with the threading section of the inner roll so as to roll the threads in the cap of proper depth. The invention possibly will be better understood by a reference to the drawings which 105 show one way of carrying out the invention.

The cap blank from which the threaded cap is formed is indicated at 1 in Fig. 1 of 110

the drawings. Said blank has a depending flange 2, the lower edge of which is bent outwardly at right angles as indicated at 3. The purpose of the invention is to form this flange of the cap with a thread, and at the same time to roll this outwardly extending part 3 into a curl. In Fig. 2 of the drawings, the finished cap is shown and the flange 2 is shown as provided with a thread 4, and the edge is turned outwardly into a curl 5. In the forming of this curl, the metal is rolled so as to conceal the raw edge of the metal, and it will be readily seen that the size of the curl will be in a measure determined by the thickness of the metal. In other words, if the metal should increase in thickness, the curl would increase slightly in thickness.

For threading and curling the cap, I have provided an inner threading roll 6 and an outer threading roll 7. These threading rolls are mounted in the well known way so that they are rotated, and the outer threading roll is given a bodily movement toward and from the inner threading roll. The inner threading roll is provided with a knurling section 7', a threading section 8 and an anvil 9 which supports the outwardly turned flange 3 while it is being rolled into a curl. This inner threading roll is of the usual construction. The outer threading roll consists of a body portion 10 which carries a knurling section 11. This knurling section 11 is in the form of a ring freely mounted on the body portion 10 as is common practice in the forming of threading rolls. Adjacent the knurling ring is a threading section 12 and adjacent the threading section 12 is a curling section 13. The parts are held assembled on the body portion by a headed bolt 14. The threading section 12 is rigidly mounted on the body portion 10 by reason of the fact that each threading section is formed with a central opening which rests on and fits against the shoulder 15 on the body portion, so that this threading section has no lateral movement whatever on the body portion 10. This is not true of the curling section 12. The shouldered part 16 passes through an opening 17 in the curling section which is larger in diameter than the shouldered part 16. This curling section is free to move laterally on the body portion 10 between the body portion and the headed bolt 14. Its lateral movement however, is limited by yielding means which as herein shown consists of a series of pins 18, each of which is provided with a conical end 19, and a spring 20 housed in a recess containing the pins normally forces the pins outwardly, that is, to the right as shown in Fig. 1. In the rear face of the curling section there is an annular groove 21, see Figures 2 and 4. This groove is V-shaped in cross section and con-

forms to a cross section of the end of the conical pins.

It will readily be seen that this curling section can be moved laterally to the position shown in Fig. 2, the pins yielding and sliding up the inclined wall of the annular groove. The spring pressure back of the pins, however, pressing on the inclined wall, will force the curling section back to normal concentric position when the lateral pressure on the curling section is relieved.

As is well known in this art, the blank from which the threaded cap is to be formed is placed on the inner roll as shown in Fig. 1. The outer roll which is rotating as well as the inner roll moves bodily into engagement with the cap and sufficient pressure is exerted on the roll to cause the metal to be threaded and curled. As has been stated above, if the thickness of the metal varies, the curl is bound to increase in diameter and thus limit the movement of the curling section of the outer roll. If this curling section of the outer roll is rigidly mounted so that it has no lateral movement, the limiting of the movement of the curling section would likewise limit the movement of the threading section, and therefore the threads would not be impressed in the flange of the cap to a uniform extent.

By my improvement, however, this outer curling section will yield under excessive pressure and permit the threading section to always come down into proper cooperative relation to the threading section of the inner roll and thus the threads will be rolled to a uniform depth even though the thickness of the metal should slightly vary.

While I have referred to variations in the thickness of the metal, it will also be noted that the variations in the length of the right angle flange 3 thus increasing the amount of metal rolled into the curl, would vary the resulting diameter of the curl, which, under the old method of making, would again hold the outer threading roll off and prevent the proper forming of the threads. By my improvement however, this variation is taken care of and the threads rolled of uniform depth.

Then again, it has been very difficult to form the outer threading roll so as to roll the curl and roll the thread of proper depth, and the rolls require constant attention and checking up so as to maintain the proper proportion of the parts to accomplish the result desired. By my improvement, however, wherein the curling section is capable of finding its proper relative position so as to turn a full curl, and at the same time permit threads to be rolled into the cap of full depth, such accuracy in manufacturing and such careful attention to maintain the proper proportions is not necessary.

It will be understood of course, that the

- tapered pins are supported by springs which are heavy enough when the roll is operating at a high rate of speed to curl the metal of the flange.
5. It is obvious that other ways of yieldingly mounting the curling section could be used, and that the present invention is directed broadly to yielding means of some character for accomplishing the results stated.
10. Having thus described the invention, what I claim as new and desire to secure by Letters-Patent, is—
1. Threading and curling devices for metal caps including inner and outer rolls having cooperating threading and curling sections, and means for supporting the curling section of the outer roll whereby the same can yield independently of the threading section of the outer roll.
  2. Threading and curling devices for metal caps including inner and outer rolls having cooperating threading and curling sections, said outer threading roll comprising a body portion, means for rigidly mounting the threading section on said body portion, and means for mounting the curling section on said body portion whereby it may yield laterally to excessive pressure.
  3. Threading and curling devices for metal caps including inner and outer rolls having cooperating threading and curling sections, the outer threading roll comprising a body portion, means for rigidly mounting the threading section on said body portion, means for confining the curling section from endwise movement of the roll, and means for yieldingly supporting said curling section whereby it may be moved laterally of the body portion under excessive pressure.
  4. Threading and curling devices for metal caps including inner and outer rolls having cooperating threading and curling sections, the outer threading roll comprising a body portion, a threading section rigidly mounted on said body portion, a curling section, spring pressed pins on which
- said curling section is mounted whereby said curling section may yield and move laterally of the body portion under excessive pressure.
5. Threading and curling devices for metal caps including inner and outer rolls having cooperating threading and curling sections, the outer threading roll comprising a body portion, a knurling ring freely mounted on the body portion so as to rotate independently of the body portion, a threading section rigidly mounted on the body portion, and a curling section yieldingly mounted on said body portion whereby said curling section may move laterally of the body portion under excessive pressure.
6. Threading and curling devices for metal caps including inner and outer rolls having cooperating threading and curling sections, the outer threading roll comprising the body portion, a threading section rigidly mounted on the body portion, a curling section secured to the body portion so that it may move laterally of the body portion, said curling section having an annular groove, V-shaped in cross section in the rear face thereof, spring pressed pins having conical ends adapted to normally register with said annular groove and hold said curling section in concentric position on the body portion, said pins yielding to excessive pressure so that said curling section may move laterally of the body portion.
7. Threading and curling devices for metal caps including inner and outer rolls having cooperating knurling, threading and curling sections, said sections on the inner roll being rigidly supported thereon, the knurling section on the outer roll being free to rotate thereon, the threading section on the outer roll being rigidly mounted thereon, and the curling section on the outer roll being yieldingly mounted thereon so that it can move laterally of the axis of the outer threading roll under excessive pressure.

In testimony whereof, I affix my signature.
THOMAS L. TALIAFERRO.
